(57) **CLAIM**

The ornamental design for a mobile headset with a pivoting microphone boom, as shown and described.

DESCRIPTION

FIG. 1 is a front-right perspective view of a mobile headset with a pivoting microphone boom according to the invention;

FIG. 2 is a front-left perspective view of the headset shown in FIG. 1;

FIG. 3 is a left elevation view of the headset shown in FIG. 1;

FIG. 4 is a right elevation view of the headset shown in FIG. 1;

FIG. 5 is a top plan view of the headset shown in FIG. 1;

FIG. 6 is a bottom plan view of the headset shown in FIG. 1;

FIG. 7 is rear elevation view of the headset shown in FIG. 1;

FIG. 8 is a front elevation view of the headset shown in FIG. 1;

FIG. 9 is a left elevation view of the headset shown in FIG. 1, showing the pivoting microphone boom located in an alternative position; and,

FIG. 10 is a top plan view of the headset shown in FIG. 1, showing the pivoting microphone boom located in an alternative position.

The broken lines in FIGS. 1, 2, 3, 4, 7, 8, 9, and 10 is for illustrative purposes only and forms no part of the claimed design.
